THREAD OPERATED STOP MOTION IN
CIRCULAR LOOMSVictor Marie Joseph Ancet, Lyon, France, assign-
or to Marius Fayolle, alias Marcel Fayolle,
Lyon, FranceApplication April 13, 1946, Serial No. 661,920
In France November 30, 1945

7 Claims. (Cl. 139—371)

1

Weft stop motions and the like thread operated means are generally executed on the principle of the dropping or rocking of a light member normally held back through the tension of the thread to be controlled and which, when it drops or rocks at the moment of the cancellation of said tension, i. e. when the thread breaks, produces through the agency of a mechanical or electrical system the stoppage of the loom.

The arrangement forming the object of my present invention is novel through the fact that the rocking member carried by the shuttle or the like moving member is separated from the parts on which it is to act through a sheet of threads adapted to move with reference to said shuttle; said feature allows my invention to be more particularly adapted to circular looms wherein the shuttle carrying the weft thread and progressing inside the shed is separated from the members driving it through one of the annular sheets of warp thread, generally the inner sheet.

My invention covers therefore a novel mechanism allowing sensing or detecting, through said sheet of threads and without disturbing operation, the dropping or rocking of the movable member carried by the shuttle.

This mechanism comprises chiefly a rotary part or drum carried by the shuttle driving member and accompanying it on the outside of the shed. Said part is provided at its periphery with one or more projecting fingers adapted to periodically engage during the rotation of said part for sensing purposes through the sheet of threads and to sweep over a certain part of the location of the movable member carried by the shuttle, whereby when said movable member has fallen or rocked, the hindrance provided thereby for the passage of said sensing finger leads to a change in the position of the latter which change is made use of for stopping the loom.

My invention also covers a particularly interesting form of execution of my invention under the form of an electrical weft stop motion or the like wherein

(a) The sensing fingers or at least one of them is carried by a pivoting axis held in position by a spring and the displacement due to the meeting between said finger and a hindrance during its circular movement closes an electric contact; this arrangement is completely enclosed underneath an easily removable protecting hood preventing any introduction of thread waste inside the mechanism, which would risk preventing its operation.

(b) The movable member pivotally secured to

2

the shuttle and held raised through its engagement against the weft thread is advantageously constituted by an arch-shaped member which is urged laterally by a spring always in the same direction, in antagonism with the retaining action produced by the tension of the weft thread bearing on the other hand against a stationary member also constituted by an arch-shaped member located in the plane of progress of the shuttle and inside which the movable hoop may be inscribed.

My invention will be better understood by referring to the accompanying drawings illustrating a form of execution thereof disclosed merely by way of example and by no means in a limitative sense. In said drawings:

Fig. 1 illustrates in a diagrammatical manner and in partly sectional elevational view a shuttle adapted to move in the plane of the drawing with its movable member raised.

Fig. 2 is a view at 90° of this same movable member in its rocked position.

Fig. 3 illustrates for the same position of the movable member the whole arrangement with its rotary sensing drum.

Fig. 4 is a perspective view from above, the cover of the drum being partly torn off.

Figs. 5 and 6 are two diagrams illustrating two positions corresponding to normal operation and to release of the inner mechanism of the drum.

As apparent from the drawing, the movable member 1 which is arch-shaped is pivotally secured at 2 to the cradle 3 of the shuttle 4. It is submitted to the action of a light spring 5 and is provided at its periphery with a folded portion 6. This movable member 1 is surrounded by a second stationary arch-shaped member 7 located in the plane of progress of the shuttle.

The weft thread 8 passing out of the shuttle between the feet of said members 1 and 7 passes behind the arch 1 and in front of the arch 7 whereby the tension exerted on said thread causes it to raise the arch 1 into the plane of the arch 7. On the contrary when the thread breaks or is released, the movable member 1 rocks under the action of its spring 5 and rests lying flat against the terminal surface of the shuttle carrying cradle 3.

The drum is constituted by a circular plate 10 keyed to a shaft 11 adapted to pivot with reference to a plate 12 carried by an upright 13 rigid with the driving member 9 of the shuttle and accompanying thus the latter on the outside of the inner sheet of threads 14 forming the shed. The shaft 11 is aligned with the shaft of one of the shuttle driving rollers 15 and its rotary movement

is transmitted thereto by said roller through a driving member 16 engaged by a fork 17. One or more projecting fingers 18, two in the case illustrated, are mounted on pivots 19 so that they may receive a radial setting with reference to the plate 10. These fingers project sufficiently beyond same for engaging periodically the sheet of threads 14 by reason of the rotation of the plate 10, said fingers sweeping furthermore a certain portion of the zone occupied by the movable member 1 when the latter is in its rocked position. The length of projection of the fingers is moreover adjustable by acting on the set-screws 20 or through any other suitable means.

The pivot 19 for each of the sensing fingers 18 extends above the plate 10 and carries a hook 21. A spring 22 connects the hooks corresponding to the two fingers and holds them facing one another so as to suitably angularly position the sensing fingers. Two collapsible stops 23 allow the rotation of the pivots 19 only in one direction, while they serve for stopping said pivots at the end of their stroke in the opposite direction and holding them against movement.

In the medial portion of the spring 22 is inserted a contact piece 24 located underneath a co-operating metal contact member 25 appearing under the shape of an upside down U carried by a removable cover 26 adapted to completely conceal the plate 10. This contact member 25 is insulated with reference to the remaining parts and is rigid with a tapered screw 27 to which electric current is fed through a hollow bronze thrust member 28 carried by the end of a spring blade 29 carried in its turn by a small pillar 30 electrically insulated with reference to the plate 12 to which it is secured. Current is fed to said pillar through a terminal 31 while its return is operated through grounding.

The operation of this arrangement is easy to understand. As a matter of fact, when the weft thread breaks, the movable member 1 is no longer held in its raised position and rocks under the action of gravity and of the spring 5. It drops and falls flat on to the upper surface of the cradle 3 (Figs. 2 to 4). Its folded portion 6 lies thus in the zone swept by the sensing fingers 18 and when it meets the first of the latter, said finger is deflected out of its normal path whereby the corresponding pivot 19 is caused to rotate in antagonism with its spring 22. This rotation is sufficient for the contact piece 24 to engage one of the arms of the U-shaped contact piece 25, which has for its action to close through the ground the electric circuit feeding the arrangement.

This temporary closing of the electric circuit is made use of by a sensitive relay for actuating the electro-mechanically released means adapted to stop the loom.

Obviously the above form of execution of the electric contact maker is illustrated only in order to disclose more clearly my invention as described and illustrated, but it may obviously be of any other suitable type.

It is also possible to provide for a purely mechanical stoppage-providing means; for instance, the central pivot may be slightly raised under the action of the rotation of one of the fingers, and thereby urge a light member forming the staple member of any suitable catch system.

As to the deflection of the sensing fingers 18, described as executed through a pivoting action in the plane of rotation of the drum, it may as well be executed through a translational movement of said fingers in parallelism with one an-

other, the fallen part of the movable member 1 forming in this case an incurved surface imparting to said fingers a slight receding movement through their tips. This fallen part may also appear under the shape of a slope which, when engaged by the fingers through its lower end, constrains them to slightly rise above their plane of rotation.

Obviously, on the other hand, it is possible to take into account the diameter of the drum and to provide only for a single sensing finger, in which case the opposite end of the spring 22 is secured, to a stationary point, while the contact piece 25 is provided with a single contacting portion.

Lastly and in a more general sense, my invention is by no means limited to the sole forms of execution disclosed hereinabove merely by way of example and it covers on the contrary all the modifications thereof whatever may be the manner of operating the deflection of the sensing finger, whatever may be their mounting and the manner of making use of said deflection for causing a stoppage of the loom and also whatever may be the design of the movable member carried by the shuttle carrier.

What I claim is:

1. In combination with a loom, the provision of means comprising a shuttle, shuttle driving means, a rotary member carried thereby for following the shuttle on the outside of the shed while rolling over same, at least one peripherally projecting sensing finger adapted to engage periodically the inside of the shed in front of the location of the shuttle, a movable member carried by the shuttle, means whereby the breaking of the weft thread produces a movement of said movable member into engagement with the sensing finger, means whereby said engagement with the movable member shifts the position of the sensing finger and loom stopping means adapted to be operated by this change in position of the sensing finger.

2. A weft stop motion system for circular looms comprising a shuttle, a driving member for the shuttle, a rotary member eccentrically carried thereby in contact with the outside of the shed for rolling in contact therewith in the vicinity of the location of the shuttle, at least one peripherally projecting sensing finger carried by said rotary member for engaging periodically the inside of the shed in front of the location of the shuttle during the rotation of said rotary member, a movable member carried by the shuttle, means whereby the breaking of the weft thread produces a movement of said movable member into engagement with the sensing finger for shifting the latter, means associated with the sensing finger and loom stopping means adapted to be operated by last mentioned means when controlled by the shifting of the sensing finger.

3. A weft stop motion system for circular looms comprising a shuttle, a driving member for the shuttle, a rotary member eccentrically carried thereby in contact with the outside of the shed for rolling in contact therewith in the vicinity of the location of the shuttle, at least one peripherally projecting sensing finger, a pivoting axis on said rotary member carrying said finger, a spring urging said finger into its normal inoperative projecting position for which it engages periodically the inside of the shed in front of the location of the shuttle during the rotation of said rotary member, a movable member carried by the shuttle, means whereby the breaking

of the weft thread produces a movement of said movable member into engagement with the sensing finger for shifting the latter, an electric switch controlled by the spring acting on the projecting finger, loom stopping means and a circuit controlling same and controlled by said switch when operated by its spring.

4. A weft stop motion system for circular looms comprising a shuttle, a driving member for the shuttle, a rotary member eccentrically carried thereby in contact with the outside of the shed for rolling in contact therewith in the vicinity of the location of the shuttle, at least one peripherally projecting sensing finger carried by said rotary member for engaging periodically the inside of the shed in front of the location of the shuttle during the rotation of said rotary member, a movable member carried by the shuttle, means whereby the breaking of the weft thread produces a movement of said movable member into engagement with the sensing finger, means operatively associated with the sensing finger loom stopping means adapted to be operated by last mentioned means when controlled by the shifting of the sensing finger and a removable hood protecting the sensing finger and associated means against the introduction of thread waste.

5. A weft stop motion system for circular looms comprising a shuttle, a driving member for the shuttle, a rotary member eccentrically carried thereby in contact with the outside of the shed for rolling in contact therewith in the vicinity of the location of the shuttle, at least one peripherally projecting sensing finger carried by said rotary member for engaging periodically the inside of the shed in front of the location of the shuttle during the rotation of said rotary member, a movable arch-shaped member carried by the shuttle and held in its inoperative position by the tension of the weft thread, a spring acting in antagonism with the tension of the weft thread on said arch-shaped member for collapsing same when the weft is broken, means whereby the breaking of the weft thread produces a movement of said movable arch-shaped member into engagement with the sensing finger for shifting the latter, means operatively associated with the sensing finger and loom stopping means adapted to be operated by last mentioned means when controlled by the shifting of the sensing finger.

6. A weft stop motion system for circular looms comprising a shuttle, a driving member for the shuttle, a rotary member eccentrically carried thereby in contact with the outside of the shed for rolling in contact therewith in the vicinity of

the location of the shuttle, at least one peripherally projecting sensing finger carried by said rotary member for engaging periodically the inside of the shed in front of the location of the shuttle during the rotation of said rotary member, a movable arch-shaped member carried by the shuttle and held in its inoperative position by the tension of the weft thread, a spring acting in antagonism with the tension of the weft thread on said arch-shaped member for collapsing same when the weft is broken, a member rigid with the shuttle adapted to guide the weft thread, means whereby the breaking of the weft thread produces a movement of said movable arch-shaped member into engagement with the sensing finger for shifting the latter, means operatively associated with the sensing finger and loom stopping means adapted to be operated by last mentioned means when controlled by the shifting of the sensing finger.

7. A weft stop motion system for circular looms comprising a shuttle, a driving member for the shuttle, a rotary member eccentrically carried thereby in contact with the outside of the shed for rolling in contact therewith in the vicinity of the location of the shuttle, at least one peripherally projecting sensing finger carried by said rotary member for engaging periodically the inside of the shed in front of the location of the shuttle during the rotation of said rotary member, a movable arch-shaped member carried by the shuttle and held in its inoperative position by the tension of the weft thread, a spring acting in antagonism with the tension of the weft thread on said arch-shaped member for collapsing same when the weft is broken, an arch-shaped member rigid with the shuttle and lying in its medial plane for guiding the weft thread and inside which the movable arch-shaped member is adapted to collapse when the weft breaks, means whereby the breaking of the weft thread produces a movement of said movable arch-shaped member into engagement with the sensing finger for shifting the latter, means operatively associated with the sensing finger and loom stopping means adapted to be operated by last mentioned means when controlled by the shifting of the sensing finger.
